UNITED STATES PATENT OFFICE.

BENJAMIN D. BOOVER, OF HAVERHILL, MASSACHUSETTS.

SOLE-EDGE TRIMMER.

SPECIFICATION forming part of Letters Patent No. 268,858, dated December 12, 1882.

Application filed April 13, 1882. (Model.)

To all whom it may concern:

Be it known that I, BENJAMIN D. BOOVER, of Haverhill, in the county of Essex and State of Massachusetts, have invented a new and useful Improvement in Sole-Edge Trimmers for Boots and Shoes, of which the following is a specification.

The object of my invention is to combine in one tool the means of trimming a round, a beveled, or square edge, as desired, of a boot or shoe sole.

The invention consists of a guard of peculiar construction, used in connection with another guard and a cutter, so that by a simple change of location of the parts the cutter can be made to trim a boot or shoe sole with a round, a beveled, or square edge.

In the accompanying drawings, Figure 1 represents a side view of the tool when arranged to cut a round edge. Fig. 2 is a front view of same, looking toward the cutting-edge of the knife. Fig. 3 represents a front view of the tool arranged for cutting a beveled edge. Fig. 4 shows the tool arranged for cutting a square edge; Fig. 5, views of the curved knife. Fig. 6 is a view of the straight knife; Fig. 7, views of the back guard; Fig. 8, views of the guard; Fig. 9, views of the angle-piece.

A is a handle, into which is fitted a knife or cutter, B, constructed with a curved portion at or near the upper end, as shown in Fig. 5.

C is what I term a "back guard," which is curved at its upper end, as shown separately in Fig. 7, so as to allow the shavings to escape freely from the cutter, and the end c projects over, as shown, against which projecting end the cutter B abuts; or it may be fitted in a notch or groove made in the said projecting edge c. The cutter B has a slot, b, at one side, through which passes a screw, d, by means of which and the washer a the guard C is secured to the cutter B, the slot admitting of an adjustment of guard C to cut more or less deep into the sole-edge. The guard C is provided with a projecting edge, g, against which the edge of the cutter fits.

At one side of the guard C is arranged a guard, E, (Shown in detail in Fig. 8.) This guard E is provided with a curved portion, h, which acts as the guard, and a straight portion, j, which serves as a guide. The guard E is secured in position by means of screws ff entering the guard C and passing through the holes e, which are made large enough to allow of the guard E being adjusted in any desired position relatively to the cutting-edge of the cutter B. On the opposite side of the back guard, C, is secured the angle-piece F, which serves as a bearing to the back of the curved cutter B.

In Fig. 3 the tool is shown as arranged for cutting a beveled edge, in which case the straight knife or cutter B' is used, as shown in Figs. 3 and 4, and abuts against the under side of the portion e, or may be fitted in a notch in the same, and is held against the projection g, the position of the angle-piece F being changed so as to overlap the rear edge of the cutter B', and the guard E being in the same position as when the tool is used with the curved cutter B.

In Fig. 4 the tool is shown as arranged for cutting a straight edge, the only change required from the position shown in Fig. 3 being the reversing of the guard E, so as to bring the straight part j against or near the cutting edge of the cutter B', as shown.

What I claim as my invention is—

A sole-edge trimmer constructed with a back guard, C, carrying the reversible guard E, having one straight side, j, and one curved side, h, and the angle-piece F, and adapted to accommodate a straight or a curved knife, substantially as and for the purpose set forth.

In testimony whereof I have signed my name to this specification in the presence of two subscribing witnesses.

BENJAMIN D. BOOVER.
